METHOD FOR MAKING IMPRESSIONS OF
OBJECTS

Warren J. Mead, Belmont, Mass.

Application September 20, 1944, Serial No. 555,010

2 Claims. (Cl. 18—55.05)

1

This invention relates to the art or method of making moulds or impressions of the complete or partial form of objects.

The invention provides a novel mode of making a quick, accurate impression or mould of an object whose form it is desired to reproduce, from which impression a casting may be made of suitable material, such as plaster or wax, or a pattern or replica of an object may be made from a mould and used in making other moulds.

To practice the invention the procedure to be followed may be briefly and in general terms stated thus: the object, an impression of which is desired, and a thin, flexible and extensible wall of an impervious container enclosing a deformable mass of mixed granular material and fluid, are pressed into contact one with the other, so that the flexible wall and its underlying mass of granular material and fluid conform to the shape of the surface of the object. The granular mass in its thus conformed shape is then solidified by reducing the pressure of the fluid.

There are two exemplifications of the procedure, similar in principle, for carrying out the invention, one suitable for obtaining an impression or mould of an exterior surface of the object, and the other suitable for obtaining an impression of an interior surface of an enclosed cavity.

If an impression of an exterior surface is desired, the object is pressed against and into a thin, flexible, extensible wall of an impervious container enclosing a deformable mass of mixed granular material and fluid so as to force the wall into the underlying mass, thereby to form an impression of the shape of the object, and then, while the impression is maintained by the presence of the object, the pressure of the fluid is reduced sufficiently to solidify the granular mass. When the object is withdrawn the impression persists as long as the low pressure within the container is maintained, and a casting may be made of the impression, thereby producing a facsimile of the shape of the object which has been pressed into the wall of the container. Obviously the same result would be obtained by pressing the container wall against the object as by pressing the object against the container wall.

If an impression is desired of the interior surface of an enclosed cavity (closed excepting for an inlet passage), such as that of a two-part or multiple part mould used in foundry work, a sack made of sheet rubber or other suitable flexible and extensible material is inserted into the cavity of the two-part mould and inflated so that it con-

2

forms with the interior surface of the mould. Into this inflated sack fine sand or other granulated material is introduced and shaken or vibrated so that it completely fills the sack and is in a condition approaching dense or close packing. The fluid (liquid or gas) is then partially evacuated from the sack and the sack is sealed, the plaster mould opened, and the rigid, sand-filled sack becomes a pattern about which a sand mould, or similar type of mould, can be built and consolidated, after which the neck of the sack is opened, the sand poured out, and the rubber sack withdrawn. This operation may be repeated indefinitely to produce multiple moulds.

15 The principle of the solidification of an enclosed granular mass by reducing the pressure of fluid mixed with it is related to the phenomenon known as dilatancy, which is the property of granular masses to expand in bulk with change 20 of shape due to the increase of space between the individually rigid particles as they change their relative position. If a granular mass in a condition of close packing is closely confined in a flexible, closed and impervious envelope, it will be 25 found that it resists deformation to an astonishing degree because when deformed it must increase in volume and requires more fluid than is available to fill the increased volume of voids. Fluid pressure within the container tends to be 30 reduced by any tendency to change the shape of the mass, and atmospheric pressure forces the envelope tightly about the mass, preventing dilation, increasing inter-granular friction, and inducing rigidity.

35 Similarly if, instead of being closely packed, the granules are mixed with a copious volume of fluid, liquid or gaseous, so that the mixture will be capable of being deformed or of yielding sufficiently to receive an impression conforming to 40 the shape of the object against which it is pressed, and if then the pressure of the fluid is reduced while the impression of the object is retained by the presence of the object, the granular mass will become solid or rigid and will retain the impression so long as the negative pressure is maintained.

45 The granular material may be of any suitable particle size, which size may vary from that of very fine sand to that of coarse sand. The finer the granules the more faithfully will details of the form of the object to be reproduced appear in the impression. The granules need not be of uniform size or of uniform shape; they may be round, or angular, or irregular or of any shape. 55 The granular material may be any organic or

inorganic material which has sufficient rigidity so that the individual grains themselves are not crushed or deformed during the operation of making the impression. Ordinary clean sand serves the purpose well, although for some purposes materials of lower specific gravity may be preferred.

The container may be of any suitable size and shape depending on the character and size of the object whose impression is desired. It may be made wholly of a thin, flexible, impervious, tough, and extensible or elastic sheet material, such as sheet rubber in the form of a sack, envelope or balloon. Or it may have a rigid body, of metal or plastic for example, or other air-tight and water-tight material having an opening at one side which is closed with a cover or wall formed of the flexible, impervious sheet material sealed over the opening to receive the impression. The important condition is that at least one wall of the container be made of a sheet of flexible and extensible material to receive the impression and that the container as a whole be substantially impervious to air or water.

The container should be provided with an opening or openings at which tubes or pipes may be connected through which fluid may be introduced and withdrawn. The fluid may be introduced into the container by any suitable means, and may be withdrawn from the container to reduce the fluid pressure by any suitable form of exhaust pumping device. The outlet to the exhaust line is preferably screened to prevent the escape of granular material while permitting the passage of the fluid.

The fluid may be liquid or gaseous, for example water or air, and is introduced into and mixed with the granular mass in such quantity as to loosen the grains and render the whole mixture sufficiently fluid or mobile to receive the impression of the object whose shape is to be reproduced.

By way of illustration, but not of limitation, certain embodiments of devices and apparatus for practicing the method are shown in diagrammatic or schematic form in the accompanying drawings, in which

Fig. 1 is a schematic representation of simple equipment for making impressions of an exterior surface of an object;

Fig. 2 illustrates an arrangement employing a valve-less piston pump;

Fig. 3 illustrates an arrangement employing a metal bellows pump of the Sylphon type;

Fig. 4 represents a container whose walls other than the wall to receive the impression are rigid;

Fig. 5 illustrates an adaptation of the invention to the making of a completely encircling impression of a withdrawable object;

Fig. 6 represents the application of the invention to the making of a pattern of the interior surface of an enclosed mould or cavity; and Fig. 6a illustrates one of the steps in moulding a pattern according to the procedure of Fig. 6.

Referring to Fig. 1 a container is shown in the form of a sack or balloon 1 of rubber or other suitable thin, impervious, tough, extensible, elastic material. Tightly fitted into the neck 2 of the container is a perforated rubber stopper or plug 3, into which is sealed a tube 4 having at its inner end a screen to prevent escape of the granular material and to permit the free passage of fluid in or out of the container. To the outer end of tube 4 a pipe 6 is connected leading to a three-way cock 7. Connected to the three-way

cock are also a fluid inlet pipe 8 and a fluid outlet or exhaust pipe 9. The container 1 is filled with sand or other suitable granular material and is externally exposed to the pressure of the ambient atmosphere. To make an impression or mould of an object the cock 7 is turned to open the inlet pipe 8 and connect it to the pipe 6 and to close the exhaust pipe 9. Sufficient fluid, liquid or gas, is introduced through inlet pipe 8 from any suitable source of supply under pressure to render the granular material 10 within the container 1 deformable. The object, of which an impression is to be taken, is pressed into the upper side of the container 1 and at the same time, if necessary, sufficient additional fluid may be introduced through the inlet 8 to permit desirable seating of the object. When the desired seating and impression of the object are obtained the cock 7 is turned to close the inlet passage 8 and connect pipe 6 to the exhaust passage 9, which leads to a suction device. Suction is then applied to the exhaust line 9 until a sufficient degree of negative pressure (that is to say, a pressure less than that of the fluid medium i. e. atmospheric air, which contacts the external surface of the container) is reached to cause the container 1 and its enclosed granular material to become rigid. The object is then removed. While suction is still maintained, or while the reduced pressure of the fluid within the container is maintained by turning the cock to close both passages 8 and 9, a cast of the impression may be made with plaster or other suitable material.

Instead of using separate devices for the introduction and extraction of fluid, controlled by a suitable valve arrangement as illustrated in Fig. 1, I have found that, since extremely low pressures in the container are not required for either gas or liquid, it is possible to use very simple devices by which both the introduction and extraction of fluid are accomplished by the same device.

Fig. 2 illustrates a valve-less piston-pump connected to the container. When the handle 11 of the piston 12 is pressed down it forces fluid from the cylinder 13 into the granular filled container 1. When the pressure at 11 is released the spring 14 surrounding the piston rod draws the piston upwardly and reduces fluid pressure in the container, causing the contained granular mass to become rigid.

Another valve-less device is illustrated in Fig. 3, which shows metal bellows 15 of the Sylphon type connected through a pipe to the container 1. A spring 16 normally urges the bellows toward an expanded position. When the bellows and spring are compressed fluid is forced from the bellows into the container. When the bellows and spring are released the increased volume of the bellows produced by the extension of the bellows developed by the spring produces a sufficiently low pressure in the container to cause adequate solidification of the granular material. This form of device is usually suitable for use only with a relatively small container.

Fig. 4 illustrates still another form of container consisting of an impervious vessel 18 made of metal, plastic or other suitable rigid material, open at the top side. The opening is covered by a sheet of flexible, elastic material 19 such as rubber. The cover sheet 19 is sealed across the open side of the container 18, as by cement and a band 17 tied under a beaded edge of the container vessel 18. The object, of which a mould 75 is desired, is pressed into the sheet and with the

sheet into the underlying granular material 10. A small space is preferably left between the sheet and the normal level of the granular material to permit the rise of displaced granules when the object is inserted. An inlet pipe 20 is provided for introducing fluid to loosen the granular material and render it deformable, and an exhaust pipe 21 leads to a suction device by which fluid may be withdrawn and the mould thereby consolidated.

An adaptation of the invention to the making of a completely encircling impression of an object which is so shaped as to be capable of being withdrawn after the granular mass has become rigid is illustrated in Fig. 5. Specifically, the object 22 shown in Fig. 5, may be the stump of an amputated leg. 23 represents a tubular casing, which is preferably conical or tapered in shape, made of metal or other suitable material. Within the casing 23 is a lining or tubular wall 24 of sheet rubber or other suitable flexible, elastic, impervious material. The wall 24 is sealed to the lower end of the casing 23, as by folding it around the lower end of the casing and tightly tying it by means of an encircling cord or band 25 above the beaded end of the casing. Granular material 10, such as sand, is introduced into the annular space between the wall 24 and the casing 23 and the upper end of the tubular wall 24 is then folded down over the top end of the casing as indicated at 24' and sealed to the casing by tying it by a cord or band 26 underneath the beaded top end of casing, thus forming a closed annular container filled with a deformable mass of mixed granular material and air, or other fluid if desired. The object 22, such as the stump of an amputated leg, is then pressed down into the bore of the device while the granular mass is deformable and makes its impression in the flexible wall 24 and the surrounding granular mass 10. While the object is still in position air (or other fluid if other fluid is used) is exhausted by any suitable means through suction pipe 27 and the granular mass becomes rigid. The object is then withdrawn leaving the impression of its shape, excepting the shape of its lower end. Casts may be made from this impression and used for forming sockets of artificial legs. An advantage of this method of making a cast, from which a socket of an artificial limb is fashioned, as compared with the usual method of making impressions by means of plaster or the like is that any desired amount of pressure may be exerted by the stump when the impression is taken, in contrast to a passive impression by the usual methods. The resulting socket for an artificial limb therefore fits the stump under conditions of normal load. The end of the stump 22 is left free, as indicated, since an artificial leg is usually supported by the tapering sides of the stump and not by the end which is tender or sensitive.

Instead of a conical casing 23 a cylindrical or other non-tapering form of casing might be used, in which case the mass of granular material for use with a tapering or withdrawable object would be thicker at the lower end of the device and would diminish in thickness toward the top.

Fig. 6 illustrates the use of the invention in the making of a pattern of the interior surface of an enclosed mould or cavity. In foundry work it is sometimes desired to produce multiple sand moulds of an irregular flask-shaped object. From a pattern of the object a plaster mould is first made. The mould is cut so that it may be

separated and reassembled. Into the air filled cavity of this plaster mould, consisting of the assembled two parts 28 and 29, a rubber sack 30 is inserted and inflated so that it conforms with the interior surface 31 of the mould the air initially filling the cavity readily escaping at the parting of the mould. Into this inflated sack fine sand or other granular material 10 is introduced (Fig. 6a) for example, it may be supplied from a reservoir R through a valved conduit P and shaken or vibrated so that it completely fills the sack and is in a condition approaching close packing. The sack is then evacuated through pipe 32 and sealed, as by tying its neck 33, the plaster mould opened, and the rigid sand-filled sack becomes a pattern about which a sand mould, or similar type of mould, can be built, after which the neck of the sack is opened, the sand poured out and the rubber sack withdrawn.

Obviously the size and shape of the container may be varied almost indefinitely and adapted to the size and shape of the object whose impression is desired; and the devices for introducing and withdrawing the fluid may be of many forms and may be hand operated or mechanically operated, as appears most appropriate or convenient to the work in hand.

A two-part mould may be made by using two containers filled with granular material, one below and one above the object. The procedure of forming the impressions of the object is substantially the same as already described. If desired the upper container may be mechanically lifted and returned to its original position by any suitable lifting device. A cast is obtained by filling the assembled two-part mould with plaster or other suitable casting material after the object has been removed from the mould sections.

The invention lends itself to a great variety of useful purposes.

One of the important uses of this means of obtaining impressions and thereby casts, is in the making of impressions of the stumps of amputated legs or arms.

Another application is in connection with making impressions of the human foot for orthopedic purposes. Here the shape of the foot under load obtainable by this method has an advantage over a passive impression.

Casts of the head or face or any part of the body can be made by using suitable sized flat containers which can be easily applied and properly adjusted, solidified and removed quickly and with a minimum of discomfort.

The invention also has useful applications in connection with dental prosthetics. By using a very thin walled container with fine granular material an impression of the gums can be made and any desirable amount of pressure by the gums can be exerted when the impression is obtained.

Individual grips for tools, guns, golf clubs and other articles which it is desirable to have conform to the hand of a particular user may be quickly and accurately made from the impression of the user's hand made by grasping a suitably sized cylindrical container.

In art work or archeology the possible applications of the invention are obvious for reproducing forms or inscriptions.

In connection with mechanical operations the invention may be used to obtain quick impressions of certain types of machine parts. And in science the invention may well be used in making impressions of any solid object, either in the

laboratory or in the field by means of a portable outfit.

Other applications will immediately occur to one desiring to obtain a quick and accurate impression of almost any object.

An important advantage of this method of making impressions is that it can be done very quickly and without the application of moisture, liquid, grease or other material or matter to the object to be reproduced.

I claim:

1. That method of making an accurate cast of the peripheral surface of the stump of the amputated leg of a living person while said stump is sustaining approximately one-half of the weight of the person, said method comprising as steps, providing a receptacle having a flexible, vertically elongate tubular inner wall, open at its upper end and which defines a deformable socket which tapers downwardly in diameter and which is of such normal dimensions as to permit the stump to be introduced into it, said receptacle containing fluid and a mass of granular material which contacts the outer surface of said flexible, tubular inner wall, pushing the stump down into said socket and into contact with the inner surface of said tubular inner wall and sustaining approximately one-half of the person's weight upon the stump by the contact of the peripheral surface of the stump with the flexible wall which defines the socket whereby said flexible wall is conformed accurately to the contour of said peripheral surface, while the latter is under normal load, solidifying the granular material by reducing the fluid pressure within the receptacle, withdrawing the stump from the socket while maintaining the reduced pressure within the recep-

10
15
20
25

tacle, and, while still maintaining such reduced pressure, forming a cast of the socket-defining wall.

2. A device for use in the practice of the method of claim 1 comprising a vertical, elongate tubular rigid casing open at the top, a thin flexible tubular elastic lining within the casing, the upper and lower edges of the lining being secured fluid-tight to the casing, the annular space between the casing and lining containing fluid and a mass of granular material, the inner diameter of the lining being such as to admit the stump of an amputated leg, the lining and granular material which contacts it assuming the contour of the peripheral surface of the stump when the latter is forced down into the tubular lining under the weight of the body, and means operative to reduce the fluid pressure within said annular space thereby to solidify the granular mass.
